UNITED STATES PATENT OFFICE.

MANUEL C. MACHADO, OF MORRO, CALIFORNIA.

RIVETING-MACHINE.

SPECIFICATION forming part of Letters Patent No. 758,263, dated April 26, 1904.

Application filed May 22, 1902. Serial No. 108,518. (No model.)

To all whom it may concern:

Be it known that I, MANUEL C. MACHADO, a citizen of the United States, residing at Morro, in the county of San Luis Obispo and State of California, have invented a new and useful Riveting-Machine, of which the following is a specification.

The present invention relates to improvements in riveting-machines, and is especially designed to facilitate the riveting of keeper-loops to harness-straps, although capable of any character of leather-riveting.

It is, furthermore, designed to provide for holding keeper-loops to the part to which they are to be attached during the riveting operation and also to maintain the same in proper relation with respect to the plunger and the anvil of the machine.

Another object resides in having the work-holder adjustable with respect to the plunger of the machine so as to accommodate for different thicknesses of leather and also to arrange the die upon the work holder so as to be adjustable therewith, and thereby accommodated to the different lengths of rivets.

Another object is to provide for turning the rivet so as to give a screw action thereto, and thereby facilitate the thrust of the rivet through the leather.

A final object is to embody the invention in the form of an attachment for application to a hand riveting-machine without materially altering the same and at the same time increasing the efficiency thereof.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of a hand riveting-machine embodying the present invention. Fig. 2 is a sectional view taken in the plane of the plunger and showing a strap and keeper-loop applied there-

to in position to be riveted. Fig. 3 is a detail perspective view of the work-holder.

Like characters of reference designate corresponding parts in all the figures of the drawings.

Referring to the accompanying drawings, 1 designates the body of the riveting-machine, which is substantially U-shaped, so as to provide the upper and lower substantially parallel arms 2 and 3, respectively. From the outer end of the lower arm there depends a sleeve or tubular bearing 4, and from the outer end of the upper arm rises a corresponding sleeve or tubular bearing 5, the bores of which are alined. Each of these bearings is internally screw-threaded, and within the lower sleeve is mounted a screw-threaded plunger 6, having its lower end provided with a hand-wheel 7, whereby the plunger may be conveniently operated. This plunger is preferably made in two sections, of which the upper section 8 is smooth and case-hardened, so as to withstand the wear of the rivets. The lower end of the section 8 is provided with a socket *a*, the outer marginal edge of which is beveled inwardly, so as to receive the tapered upper end *c* of the section 6, whereby the frictional engagement between the two plunger-sections will be sufficient to rotate the upper section 8 for a purpose as will be hereinafter described. The upper end of the plunger-section 8 is provided with a socket or recess *d*.

Within the upper bearing 5 there is provided a screw-threaded stem or shank 9, which is provided at its outer end with a head or finger-piece 10 for convenience in adjusting the stem in an endwise direction through the bearing. This stem carries the work-holder, which is in the form of an arm 11, substantially parallel to the stem and provided with an upper laterally-directed terminal bearing projection 12, which is provided with a perforation for the reception of the upper portion of the stem, whereby the latter may be rotated independently of the work-holder. The opposite lower end of the work-holder is provided with a pair of laterally-projected jaws 13, to the upper of which the lower end of the stem is swiveled, preferably by means of a tapered projection *e*, fitting in a tapered

opening *f* in the upper jaw 13, whereby the stem 9 will always be properly centered, although the projection and opening may become worn. The lower jaw is provided in its 5 lower or outer face with a depression or seat 14, in the center of which is a projection 15, which is of conical shape.

At the rear end of the U-shaped body there is provided an integral solid lateral extension 10, which is provided at its outer end with an engaging face and which projects above or beyond the arm 2, so as to form a hammer-head 20 for use in hammering rivets into a piece of leather and, in fact, in the capacity of a hammer for any purpose whatsoever.

In employing the present device for securing a keeper-loop to a harness-strap, as indicated in Fig. 2 of the drawings, the strap 16 and the overlapped portions of the looped 20 keeper 17 are placed between the lower end of the work-holder and the plunger, with the intermediate portion of the keeper received in the seat or opening between the jaws 13, a rivet 18 having been previously fitted in the 25 rivet-seat formed by the upper end of the bearing-sleeve for the plunger. It will of course be understood that the holder is adjusted toward or away from the plunger by means of the endwise-adjustable stem 9, so as to accommodate the holder to the thickness of the 30 leather, after which the plunger is operated to force the rivet through the strap and the overlapped portions of the looped keeper, whereby the end of the rivet enters the seat 35 or depression in the anvil and is offset by engagement with said seat and the central projection 15. It will be noted that the head of the rivet overlaps the edges of the socket *d* in the upper end of the plunger-section 8, 40 whereby the hard edges of the socket will bite into the comparatively soft head of the rivet, and thereby turn the same with the plunger, whereby the rivet is screwed through the leather strap instead of merely being forced 45 therethrough, thus materially facilitating the setting of the rivet through the leather. As soon as the upper end of the rivet strikes the jaw 13 and begins to be upset both the rivet and the plunger-section 8 will thereby be held 50 against rotation, so as not to interfere with the upsetting of the rivet.

From the foregoing description it will be noted that the work-holder is conveniently adjustable toward and away from the plunger, 55 so as to accommodate for the different thicknesses of straps and keeper-loops, and the holder is swiveled or pivotally connected to the adjustable stem, so as to obviate a swinging movement of the holder during the rotatable movement required to adjust the stem. Moreover, by reason of this pivotal mounting 60 of the holder upon the stem the former may be swung to opposite sides of the device, so that it may be conveniently used in either hand.

65 To provide for convenience in applying and

removing the work-holder, the finger-piece 10 is made removable and is provided with a stem having a smooth cylindrical portion 22 to rotatably fit in the bearing-opening in the arm 12, the outer end of the stem being reduced and screw-threaded, as at 21, to fit in a corresponding screw-threaded socket in the top of the shank 9, it of course being understood that the screw-threads on the stem 21 correspond in direction with respect to the 75 screw-threads on the shank 9 in order that the finger-piece 10 may not be loosened when it is operated to feed the shank 9 downwardly. When the finger-piece has been removed, there is sufficient looseness between the arm 11 and the shank 9 to permit of the former being easily removed from the latter, and then the shank may be removed from the bearing 5.

A very important feature of the present invention resides in the peculiar proportion of 85 the work-holder 11, whereby it is impossible for the seat 14 and the projection 15 to come in contact with the plunger-section 8 and the lower arm 3, as such engagement of parts would soon result in damage to the seat and 90 projection. To bring about this feature, the work-holder 11 is constructed to have the length from the under side of the arm 12 to the lower side of the holder slightly less than the distance between the top of the arm or 95 bearing 5 and the top of the lower arm 3, whereby when the holder has been adjusted downwardly until its arm 12 strikes the top of the arm 5 the lower end of the holder will not quite reach the arm 3, and therefore it is 100 impossible for the seat 14 and projection 15 to contact with the case-hardened plunger-section 8.

It will of course be understood that the combined plunger-sections are slightly longer 105 than the part 4 in order that the rivet may be moved out of the bore of said part and into engagement with the anvil in order that it may be upset thereby.

What I claim is—

1. A riveting-machine, having a plunger and a horizontally-movable work-holder which is longitudinally adjustable toward and away from the plunger and means for supporting the work-holder in its adjustment.

2. A riveting-machine, having a plunger and a rotatably-mounted work-holder which is adjustable toward and away from the plunger and is also capable of rotatable adjustment to swing to opposite sides of the machine.

3. A riveting-machine, having a plunger, a horizontally-movable work-holder to cooperate with the plunger, and a longitudinally-adjustable screw-threaded stem alined longitudinally with the plunger and carrying the 125 work-holder and supporting the same.

4. A riveting-machine, having a plunger, an adjustable screw-threaded stem alined longitudinally with the plunger, and a work-holder swiveled upon the stem.

5. A riveting-machine, having a plunger, a screw-threaded adjusting-stem alined longitudinally with the plunger, and a work-holder embodying an arm having its outer end provided with a lateral projection which is swiveled to the outer end of the stem, and a pair of laterally-projected jaws carried at the opposite inner end of the body and forming the work-holder proper, the inner end of the stem 10 being swiveled to the inner jaw, and the outer side of the outer jaw being provided with an anvil to coöperate with the plunger.

6. A riveting-machine comprising a substantially U-shaped body having its opposite ends provided with transverse interiorly-screw-threaded and alined tubular bearings, a screw-threaded plunger working in one of the bearings and provided at its outer end with a hand-wheel, a screw-threaded stem working 15 in the opposite bearing, and a work-holder embodying an arm lying substantially parallel with the stem, and provided with an outer lateral projection swiveled to the outer end of the stem, and a pair of holder-jaws projected laterally from the opposite end of the body, the inner jaw being swiveled to the inner end of the stem, and the outer jaw having an anvil 25 provided upon its outer side.

7. In a riveting-machine, the combination 30 with a frame, and a plunger, of an arm having a laterally-projecting perforated portion at one end and provided with a pair of laterally-projected jaws at the opposite end, the outer side of the outer jaw having an anvil formed thereon and being located opposite the plunger, and means connected with the frame and with the perforated portion for moving the arm toward and from the plunger, substantially as described.

8. A riveting-machine, having means for rotating the rivet during the riveting operation, and means for frictionally actuating the said means.

9. A riveting-machine having an endwise-movable and rotatable plunger provided with means for engaging a rivet to rotate the same, and means for frictionally actuating the said means, substantially as described.

10. A riveting-machine having an endwise-movable and rotatable plunger composed of separate sections, one of the sections being frictionally actuated and provided with a socket forming a rivet-engaging portion adapted to be partially embedded in a rivet, 55 whereby the rivet is interlocked with the frictionally-actuated section for simultaneous rotation therewith, substantially as described.

11. A riveting-machine having an endwise-movable and rotatable plunger provided in its 60 outer end with a socket which is smaller in diameter than the diameter of the head of a rivet to form a rivet-engaging portion, and means for frictionally actuating the rivet-engaging portion of the plunger, substantially 65 as described.

12. A riveting-machine, having an endwise-movable and sectional rotatable plunger, the outer section of which is constructed to engage a rivet for simultaneous rotation therewith to force the rivet through the material, 70 and the inner section being in frictional engagement with the outer section to permit the latter to be held against rotation during the upsetting of the rivet.

13. In a riveting-machine, the combination 75 with an anvil, of an endwise-movable and sectional rotatable plunger provided at its outer end with means for engagement with a rivet, and also having a frictional engagement between the plunger-sections, whereby the outer 80 plunger-section is capable of being held against rotation by the frictional engagement between the rivet and the anvil during the upsetting operation.

14. In a riveting-machine, the combination 85 with an anvil, of an endwise-movable rotatable plunger formed in separate sections, one section being screw-threaded and provided with an operating device at one end and a tapered terminal at the other end, the other 90 plunger-section being smooth and provided in its outer end with a socket and at its inner end with a socket having inwardly-beveled edges for frictional engagement with the tapered end of the screw-threaded section. 95

15. In a riveting-machine, the combination with a plunger, of a work-holder adjustable toward and away from the plunger and movable horizontally, and means for limiting the adjustment of the work-holder toward the 100 plunger to prevent contact therewith.

16. In a riveting-machine, the combination with opposite-spaced members, one of which has a plunger, of a work-holder carried by the other member and adjustable toward and away from the plunger and movable horizontally, and also provided with a stop device for engagement with said other member for limiting the adjustment of the work-holder toward the plunger and to prevent contact 105 therewith.

17. In a riveting-machine, the combination with opposite members, one of which has a plunger, and the other is provided with a screw-threaded bearing, of a work-holder having a 115 laterally-projected arm, and a screw-threaded adjusting-stem swiveled upon the arm and working in the screw-threaded bearing, the distance between the inner side of the arm and the outer side of the work-holder being less 120 than the distance between the outer end of the screw-threaded bearing and the plunger.

18. In a riveting-machine, the combination with a substantially U-shaped body, of a plunger transversely piercing one side of the body, 125 an adjustable screw-threaded stem piercing the other side of the body, and a work-holder having its outer end provided with an arm which is swiveled upon the adjusting-screw, and its inner end being provided with a pair 130

of laterally-projected work-holding jaws, the distance between the inner side of the arm and the opposite end of the work-holder being less than the distance between the first-mentioned member of the body and the outer side of the opposite portion of the body, whereby the arm forms a stop to prevent the work-holder from engaging the plunger.

19. In a riveting-machine, the combination with a support, of a plunger, an adjustable work-holder, a screw-threaded adjusting-stem mounted upon the body and carrying the work-holder, and a removable finger-piece piercing a part of the work-holder and having a detachable engagement with the screw-threaded adjusting-stem.

20. In a riveting-machine, the combination with a support, of a plunger, an adjustable work-holder having a lateral arm, an adjustable screw-threaded stem, and a finger-piece having a smooth cylindrical portion piercing

the arm of the work-holder to form a swiveled connection therewith, with the outer end of the stem screw-threaded and entering a screw-threaded socket in the outer end of the screw-threaded adjusting-stem.

21. In a riveting-machine, the combination with opposite members, of a plunger carried by one of the members and provided with a handle constructed to engage one side of the member to stop the plunger, a work-holder carried by the other member and adjustable toward and away from the plunger, and means to stop the adjustment of the work-holder before it contacts with the first-mentioned member. 35

In testimony that I claim the foregoing as my own I have hereto affixed my signature in the presence of two witnesses.

MANUEL C. MACHADO.
